(57) **CLAIM**

The ornamental design for a container having surface ornamentation, as shown and described.

DESCRIPTION

FIG. 1 is a perspective view of a container having surface ornamentation embodying our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures depict environmental subject matter only and form no part of the claimed design.

In FIGS. 1 and 2, the stippling indicates color, but not a particular color.
